UNITED STATES PATENT OFFICE.

FRANK E. WRIGHT, OF LYNN, MASSACHUSETTS.

DESIGN FOR A HEEL-DIE.

SPECIFICATION forming part of Design No. 34,625, dated June 4, 1901.

Application filed February 27, 1901. Serial No. 49,171. Term of patent 14 years.

To all whom it may concern:

Be it known that I, FRANK E. WRIGHT, of Lynn, in the county of Essex and State of Massachusetts, have invented and produced 5 a new and original Design for Heel-Dies, of which the following is a specification.

This invention relates to a new and original design for heel-dies; and it consists in the novel features of shape and configuration 50 hereinafter fully described and particularly claimed, and clearly illustrated in the drawings.

Reference is to be had to the accompanying drawing, forming a part of this application, 5 in which like characters indicate like parts wherever they occur.

Figure 1 is a perspective view of a heel-die, showing my design. Fig. 2 is a cross-sectional view on the line 2 2 of Fig. 1.

The essential feature of my design consists 20 in a heel-shaped die formed on its face with a narrow rectangular-shaped boss having parallel sides and an inclined inner end.

a represents a heel-die having a straight rear edge *b*. *c* represents a rectangular- 25 shaped boss formed upon the top face of said die and on the side *b* thereof.

I claim—

The design for a heel-die, substantially as herein shown and described. 30

In testimony whereof I have affixed my signature in presence of two witnesses.

FRANK E. WRIGHT.
